The ornamental design for a flotation device, as shown and described.

DESCRIPTION

FIG. 1 is a front perspective view of a new design for a flotation device;

FIG. 2 is a top plan view thereof;

FIG. 3 is a bottom plan view thereof;

FIG. 4 is a right side view thereof;

FIG. 5 is a left side view thereof;

FIG. 6 is a rear view thereof;

FIG. 7 is a front view thereof; and,

FIG. 8 is a cross-sectional view thereof, taken along line 16-16 in FIG. 6.

The broken lines are directed to environment and are for illustrative purposes only and form no part of the claimed design. The thin solid lines illustrate surface contour and form no part of the claimed design.

The cross-sectional view of FIG. 16 is provided to illustrate and help clarify the contour and/or configuration of the exterior design, and is not intended to illustrate interior features that are excluded from the claimed design. Any interior features that are illustrated are provided to help clarify the exterior design only, and such interior features form no part of the claimed design.
